UNITED STATES PATENT OFFICE.

HENRY B. COOLEY, OF NEW BRITAIN, CONNECTICUT, ASSIGNOR TO THE AMERICAN PAPER GOODS COMPANY, OF KENSINGTON, CONNECTICUT, A CORPORATION OF NEW JERSEY.

MECHANISM FOR FEEDING PAPER.

No. 874,943.

Specification of Letters Patent.

Patented Dec. 31, 1907.

Application filed February 8, 1905. Serial No. 244,740.

To all whom it may concern:

Be it known that I, HENRY B. COOLEY, a citizen of the United States, residing at New Britain, in the county of Hartford and State 5 of Connecticut, have invented certain new and useful Improvements in Mechanism for Feeding Paper, of which the following is a specification.

This invention relates to feed-mechanism 10 generally, and it is especially applicable to printing-presses, envelop, bag and many other machines in which paper is operated upon to produce various articles.

Primarily, the object of the invention is 15 the provision of improved feed-mechanism which will detach a sheet from a pile, and advance it to a machine of any desired kind, with which it may be employed.

A further object of the invention is the 20 provision of improved feed-mechanism working on the suction principle, and operating to detach a sheet from a pile of sheets, and to advance it to a machine in which it is utilized for any desired purpose.

25 A further object of the invention is the provision of reciprocatory feed-devices operating to detach the lowermost sheet from a pile, as will be hereinafter explained.

A further object of the invention is the 30 provision of improved buffer-devices for engaging the end of the pile.

A further object of the invention is the provision of mechanisms for actuating the picker toward and from the feed-rolls, and 35 for continuously rotating said feed-rolls.

Other objects of the invention will be hereinafter set forth.

In the accompanying drawings, Figure 1 is a plan view of the improved feed-mechanism. 40 Fig. 2 is a side view thereof. Fig. 3 is a section on line 3—3 of Fig. 1. Fig. 4 is a section on line 4, 4 of Fig. 1. Fig. 5 is a front view, part of the frame being broken away.

Fig. 6 is a partial section, taken on line 6, 6 45 of Fig. 1; and Figs. 7 and 8 are sectional views corresponding to Figs. 3 and 4, but showing the parts in different positions.

Fig. 9, Sheet 1, is a side elevation of a modification hereinafter described.

50 Like numerals designate similar parts throughout the several views.

Referring to the drawings, the numeral 5 denotes in a general way framework of any

desired construction for supporting the various parts of the machine, and shown composed of connected side-plates 5'. Secured to this framework by grooved brackets 6, into which it is slid is a broad plate or table 7, slotted at 7' for purposes hereinafter stated, and rising from said table are posts 8, 60 between which a pile of sheets 9 is placed, the forward end of said pile overlapping the end of the table, as shown in Figs. 1, 3, 4, 7 and 8.

Designated by 10 is the driving-shaft of the machine, said shaft being supported in 65 boxes of the frame and carrying a pulley 11, or other instrumentality to which power may be applied. Gears 12, 12' are secured to shaft 10 between the side plates of the frame, and loosely sleeved on said shaft adjacent to 70 gear 12 is an arm 13, and adjacent to gear 12' is an arm 13'. Mounted on studs 14, 14' of said arms are idlers 15, 15' in constant mesh with the gears 12, 12', and journaled on other studs 16, 16' carried by the arms are pinions 75 17, 17', the latter meshing with gears on feed-rollers hereinafter described. After passing through the arms 13, 13' and securing the pinions 17, 17' thereto, the ends of the studs 16, 16' are threaded into links 18, 18', the latter having bushed hubs 19, 19' sleeved loosely upon an oscillatory suction-rod or shaft 20, 80 said shaft serving to connect the links and to rock therein, as shown in Fig. 6. This shaft 20 is shown tubular for a portion of its length 85 as at 21, although it may be of pipe-form throughout, and is provided with ports 22, and surrounding said ports with a picker 23 having openings 24 communicating with the ports 22. Sleeves 25 and 26 are mounted on 90 the shaft 20 between the picker 23 and the links 18, 18', and each sleeve is provided with a gear 25', 26', respectively, in mesh with the pinions 17' and 17, and with a roller 25², 26², respectively, as illustrated in Fig. 6.

95 Secured to shaft 10 is an eccentric 27 the strap of which is connected by a rod 28 with an arm 29 projecting from a rock-shaft 30 journaled in boxes of the frame. Rigid with said rock-shaft are arms 31, 32, which are 100 articulated at their free ends to links 33 and 34, said links being connected to slides 35 and 36 movable in slots 37 of the side-plates, one of said slots being shown in Fig. 2, and said slides constituting a reciprocatory support 105 for the feed and other devices hereinafter

described. In these slides is journaled the parti-tubular shaft 20, and a shaft 38 is mounted in boxes 39 fitted in slots 39' of the slides. Springs 40 bear against the boxes 5 and the inner sides of cap-plates 41 closing the ends of the slots in said slides. Pinions 42 and 43 rigid with said shaft 38, are in constant mesh with the gears 25', 26' of sleeves 25, 26, and intermediate said pinions the 10 shaft is provided with rolls 44, 45, always bearing under yielding pressure against the rolls 25', 26' of said sleeves. A bar 46 is secured to the slides 35 and 36, and it affords a support for angle-levers 47-48, which are 15 pivoted on studs 49-50 secured to the bar, as illustrated in Fig. 5. The forward arms of these levers are curved, and each is provided with a buffer-rod or pin 51, while the rear arms are connected by a spring 52, which 20 tends constantly to force the pin 51 inward against the end of the pile of sheets 9, as illustrated in Fig. 1. Rods 53 pass loosely through the bar 46, and at their rear ends are threaded to receive nuts 54, which act as 25 stops. These rods are connected at their forward ends to a buffer-plate 55, and are surrounded between said plate and the bar 46 each by a coiled spring 56, the stress of 30 said spring tending normally to force the plate 55 forward, so that it will yield when in the operation of the devices it strikes the end of the pile 9, and therefore, will act as a buffer for that portion of the end of said pile located between the buffer-rods or pins 51.

35 Designated by 57 is a plate for aiding in separating the bottom sheet from the pile and this plate is of wedge-shape and will hereinafter be termed the "separator". At its rear end the separator is widened and is 40 slotted at 58 to receive screws 59 by which it is secured to the cross-bar 46. A thumb-screw 60 passes through a vertical flange 61, of said separator, is swiveled therein, and its threaded portion enters a nut in bar 46, 45 thereby enabling the separator to be adjusted back and forth as desired, to locate it properly to perform its office.

Rigid with the parti-tubular shaft 20 is a 50 pinion 62, the teeth of which are in mesh with a rack 63 carried by an overhanging-plate 64 secured to one of the side-frames 5'. Tubing 65 is connected to the end of shaft 20, as illustrated by dotted lines in Fig. 2, and this tubing communicates at its opposite extremity with the chamber of an exhaust-pump 66, the piston-rod 67 of which is driven by a wrist-pin 68 carried by a disk 69 rigid with the shaft 10, as usual.

60 In the modification illustrated in Fig. 9 all the parts of the mechanism are the same as in the other views, with the exception of the separator for aiding in the seizure of the lowermost sheet from the pile. This separator in shop parlance is known as the "dagger," 65 and its function is, as above stated, to assist

in the removal of the sheet, and to prevent more than one sheet from being seized by the picker.

When a construction of the kind illustrated in Fig. 9 is employed the separator 57 70 shown in Fig. 1 and other figures is, of course, omitted.

Rising from a side-plate of the machine-frame is a bracket 70, and in a bearing 71 in the forward end of said bracket is journaled 75 a rock-shaft 72. Rigid with the rock-shaft 72 is an arm 73, and in a bearing 74 at the free end of the arm is firmly secured a stub 75 from which depends a separator or "dagger" 76, in the form of a curved blade. An 80 arm 77 is clamped to the rock-shaft 71, and projects rearwardly therefrom, and to said arm is articulated a link 78, forked at 79 to straddle the driving-shaft 10. A roller 80 is mounted on a stud of the link, and said 85 roller is in contact with the periphery of a cam 81 rigid with the driving-shaft. This cam is so shaped that when the picker 23 arrives beneath the pile, the link 78 will be actuated thereby rocking the short shaft 72, 90 and carrying the dagger or separator 76 downward to coöperate with the picker in removing a sheet. As said dagger moves down its curved under surface will come into contact with the sheet seized by the 95 picker, and cause it to be cleanly separated from the pile. From what has been stated, it will be seen that the separator and picker move synchronously, that one aids the other in the sheet-separating operation, and that 100 the separator as it moves in an arcuate path lifts the pile away from the detached sheet. While particular mechanism is shown for actuating the swinging separator, the invention is not limited thereto, for other mechanical combinations may be employed as 105 substitutes if desired.

In the illustrations given the feeding mechanism is shown arranged at a certain angle, but it is distinctly to be understood 110 that the invention is not limited in this respect for it may be otherwise located if desired.

In the operation of the invention a pile of sheets is placed on the table 7 and between the posts 8 thereof, and the driving-shaft 10 is set in motion.

In Figs. 1, 2, 3 and 4 the mechanism is shown at the inception of its feeding movement, the picker 23 being beneath the bottom sheet of the overhanging end of the pile, and the ports of said picker being in a vertical position. As the driving-shaft 10 rotates, the eccentric 27 actuates the rock-shaft 30, and the arms 31 and 32 and links 33 and 34 120 are forced from the positions represented in Figs. 3 and 4 to those illustrated in Figs. 7 and 8. During this action the pinions 17, 17' and the gears 25', 26' of sleeves 25 and 26 travel in the slots 7' of the table 7 and the 130

slides 35 and 36 are simultaneously actuated to force the buffer-rods 51 and the buffer-plate 55 against the end of the pile, and to carry the separator 57 between the lower sheet and the remainder of the pile. As this takes place the pinions 14, 14' roll over the gears 12, 12', and being in mesh therewith constantly drive the geared sleeves 25 and 26 and the shaft 38. It is to be understood that suction has already been established by the pump in the tube 65 and hollow picker-shaft 20, and that when the picker is in the position represented in Fig. 4 it will attract the lower sheet of the pile. As the slides move inward the pinion 62 of picker-shaft 20 engages the fixed rack 63, and at the limit of their stroke, said picker will be rocked to the position illustrated in Fig. 8, and the end of the sheet carried by said picker will be inserted between the continuously and rapidly-rotating rollers 25²—26², 44 and 45, and will be fed by them to the machine with which the improved mechanism is in use. When the sheet is grasped by the rollers the separator 57 aids in stripping it from the pile and in guiding it as it is advanced by said rollers.

The continuously driven feed-rollers constitute an important feature of the invention, and the arrangement of the feed-mechanism as a whole is compact, of simple construction, and is reliable in operation.

While a suction-picker is shown for detaching and feeding the sheets from the bottom of the pile, the invention is not limited thereto, for by slight modifications the mechanism may be arranged to feed from the top of the pile; nor is the invention limited to the precise arrangement of operating mechanism shown and described, for various modifications may be made that will be within the purview thereof. So too, the form of the picker may be varied, and the mechanism may be arranged in vertical, horizontal or other desired positions without departure from the invention.

Having thus described my invention, what I claim is—

1. The combination, with a support for a pile of sheets, of a picker movable beneath the pile, and adapted to seize the lower sheet thereof; feed rolls sleeved on the picker-shaft; means for driving said feed-rolls; and means coöperating with said feed-rolls to seize and advance the sheet delivered by the picker.

2. The combination, with a support for a pile of sheets, of a pneumatic picker adapted to seize a sheet from said pile; a rotary shaft carrying the picker; feed-rolls sleeved on the picker-shaft for advancing the sheet delivered by the picker; complementary feed-rolls; and means for continuously rotating all of said feed-rolls.

3. The combination, with a support composed of a pair of slides, of means for simul-

taneously actuating the slides; feed-rolls movable with the slides; gearing for continuously driving the feed-rolls; and a device carried by the shaft of one of the feed-rolls for delivering a sheet to said feed-rolls. 70

4. The combination, with a sliding support, of feed-rolls movable with said support; a table for receiving a pile of sheets; a picker also movable with the support, and upon the shaft of which two of the feed-rolls are sleeved; and means for actuating said picker to cause it to detach a sheet from the pile, and deliver said sheet to the feed-rolls. 75

5. The combination, with a stationary table for receiving a pile of sheets, of a movable support, spring-controlled levers movable with the support; and buffers carried by said levers, and adapted to engage the end of the pile. 80

6. The combination, with a table for receiving a pile of sheets, of a reciprocatory support; a pair of angle-levers pivoted thereto; a spring connecting the rear arms of said levers; and buffers carried by the other arms of said levers, and adapted to engage the end 90 of the pile. 85

7. The combination, with a table for supporting a pile of sheets, of a series of buffers; means for reciprocating said buffers toward and from the table; a device for detaching a sheet from the pile carried by said means; and feed-mechanism coöperating with said device and also carried by said means. 95

8. The combination, with a stationary table for supporting a pile of sheets, of a series of buffers; a cross bar on which the buffers are mounted; a pair of slides connected by the cross-bar for simultaneously reciprocating said buffers; a picker carried by said connected slides for detaching a sheet from the pile; means for actuating the picker; and means for feeding the sheet delivered by the picker. 100

9. The combination, with a table for receiving a pile of sheets, of a shaft, a reciprocatory support for said shaft; means for actuating said shaft; feed-rolls sleeved upon the shaft; means for driving said feed-rolls; a picker carried by the shaft between the feed-rolls; and means coöperating with said feed-rolls for advancing a sheet delivered by the picker. 110

10. The combination, with a table for receiving a pile of sheets, of a picker; a shaft by which the picker is carried; sleeves having feed-rolls mounted on the picker-shaft; a driving-shaft; gearing actuated by the driving-shaft for rotating the sleeves; a shaft having a feed-roll, and driven by the sleeves; means operated by the driving-shaft for reciprocating the picker-shaft; and means for actuating said picker-shaft to cause the picker to detach a sheet from the pile, and convey it to the feed-rolls. 120

11. The combination, with a support, and 130

with feed-rolls carried thereby, of a driving-shaft; arms sleeved on said driving-shaft; means for actuating said arms; means carried by said arms for actuating the feed-rolls; means for feeding material to said feed-rolls; and means for actuating said support.

12. The combination, with a table for the reception of material, of a support; feed-rolls carried by the support; means for reciprocating the support; a picker carried by one of the feed-roll shafts; means for actuating said picker to remove material from the table and deliver it to said feed-rolls; and 15 gearing for driving said feed-rolls.

13. The combination, with a table upon which a pile of sheets is placed, of pivoted angle-levers; a spring connecting the outer arms of said levers; buffer-pins carried by 20 the other arms of said levers; a separator; a spring-actuated buffer-plate; a reciprocatory-device by which said parts are carried; and means for removing a sheet from the pile.

14. The combination, with a table for receiving a pile of sheets, of a support; a shaft carried by the support; a picker on the shaft; means for actuating said picker; feed-rolls loose on the shaft; complementary feed-rolls carried by the support; links connected to 30 the support; a driving-shaft; arms sleeved on said driving-shaft; gearing carried by the arms; gearing on the feed-rolls driven by the gearing of the arms; and means actuated by the driving-shaft for reciprocating the links.

15. The combination, with a table for receiving a pile of sheets, said table being slotted, of a picker; feed-rolls on the picker-shaft; reciprocatory means for supporting the picker-shaft; gears for driving the feed-40 rolls, said gears moving in the slots of the table; and means co-operating with said feed-rolls for advancing a sheet delivered by the picker.

16. The combination, with a table for receiving a pile of sheets, of slides movable on the frame; a driving-shaft; an eccentric on said driving-shaft; a rock-shaft actuated by the eccentric; arms carried by the rock-shaft, and connected to the slides; sheet-detaching and feeding-mechanisms carried by the slides; and means for operating said mechanisms.

17. The combination, with a table, of a suction-device; a sliding support for said device; means for reciprocating said support; means for rocking said suction-device; feed-mechanism to which material from the table is delivered by the suction-device; means for rotating said feed-mechanism; a sheet-separator, movable in synchronism with said support; and a buffer carried by said support.

18. The combination, with framework, of slides mounted thereon; feed and suction-devices movable with the slides; a driving-shaft; arms sleeved on said driving-shaft,

gears on the driving-shaft; a series of gears carried by the arms, and serving to drive the feed-devices; a rock-shaft; means for actuating said rock-shaft; arms projecting from the rock-shaft; and links for connecting said arms with the slides.

19. The combination, with framework, of slides mounted thereon; feed-rolls carried by the slides; gears for connecting said feed-rolls; a driving-shaft; arms sleeved on said 70 driving-shaft; gears on the arms, and serving to drive the feed-rolls; gearing for actuating said gears; and means actuated by the driving-shaft for reciprocating the slides.

20. Feed mechanism comprising a shaft 80 having a bore and a port communicating with said bore; a picker carried by said shaft, and also having a port; sleeves loose on the shaft, and each having a roll-surface and a gear surface; a feed-roll shaft having gears in 85 mesh with the gear-surfaces of the sleeves; means for rotating the sleeves; and means for actuating the picker-shaft, the parts being combined substantially as and for the purpose specified.

21. The combination, with a table, of a pair of slides; means for reciprocating said slides a cross-bar connecting said slides; yielding buffers carried by the cross-bar; a separator; means for adjusting said separator; 95 and feed-mechanism supported by the slides.

22. In mechanism of the class described, the combination, with a table for supporting a pile of sheets, of feed-rolls having gears; a feed-roll shaft having surfaces in engagement with the feed-rolls; a picker-shaft; a picker; a driving-shaft; arms sleeved on the driving-shaft; gears loosely mounted on studs of the arms, and a pair of which engage the gears of the feed-rolls; gears on the driving-shaft in engagement with another pair of the gears carried by the arms; links connecting the arms with the picker-shaft; a rock-shaft; slides carrying the picker-shaft and the feed-roll shaft; arms projecting from the rock-shaft; links connecting said arms with the slides; and gearing for actuating the picker-shaft.

23. The combination, with a table for supporting a pile of sheets, of slides; means for simultaneously reciprocating the slides; a tubular shaft carried by the slides; a picker communicating with the bore of said shaft; a pinion carried by the shaft; a rack with 115 which the pinion engages; feed-rolls sleeved on the tubular shaft, and to which a sheet is delivered by the picker; complementary feed-rolls; and means for rotating the feed-rolls.

24. The combination, with a support for a 125 pile of sheets, of means for detaching a sheet from the pile; a reciprocatory support composed of a pair of connected slides carrying said means; a separator movable in an arcuate path, and co-operating with the sheet de- 130

- taching means; mechanism for actuating said separator; and a buffer carried by the reciprocatory support.
25. The combination, with a support for a pile of sheets, of a pneumatic picker for detaching a sheet from the pile; means for actuating the picker; a reciprocatory support, composed of a pair of connected slides carrying said picker; a swinging separator coöperating with the picker; and continuously-acting feed-mechanism to which the detached sheet is delivered by the picker.
26. The combination, with a table for receiving a pile of sheets, of an oscillatory pneumatic picker for detaching a sheet from the pile; a reciprocatory support for carrying said picker; a swinging separator; a cam; connections between the cam and separator, and continuously-acting feed-rolls, to which the sheet is delivered by the picker.
27. In sheet-feeding mechanism, the combination, with a pneumatic picker, and with means for actuating the same, of a reciprocatory support for the picker; a swinging separator movable synchronously with the picker; a link, and connections for actuating said separator; means for operating the link; and continuously-driven feed-rolls to which the sheet is delivered.
- 30 28. In sheet-feeding mechanism, the combination, with a pneumatic picker, of a reciprocatory support for said picker; a rock-shaft; an arm rigid with said rock-shaft; a separator carried by the arm, and coöperating with the picker to remove a sheet from a pile; a link connected to the rock-shaft; a cam for actuating said link; and feed-rolls to which the sheet is delivered.
29. In feed-mechanism, the combination, with means for detaching a sheet from a pile, 40 of a reciprocatory support for said means; a separator; an arm to which the separator is attached; a rock-shaft journaled in a bearing of the frame, and carrying the arm; a second arm; a link articulated to said second arm; 45 means for actuating the link; and continuously-driven feed rolls to which the sheet is delivered.
30. The combination, with continuously-driven feed-rolls, and with means for actuating said rolls; of a shaft upon which a pair of the rolls is sleeved; a rotary picker located between the rolls; and means for actuating said picker.
31. The combination, with pairs of feed- 55 rolls, of a shaft upon which said rolls are sleeved; means for rotating said shaft; a complementary feed-roll; a rotary pneumatic picker located between the feed-rolls; means for actuating said picker; and a table for supporting a pile of sheets.
32. The combination, with a support for a pile of sheets, of a picker for detaching the bottom sheet from the pile; feed-mechanism embodying a shaft; a pair of feed-rolls 65 sleeved on said shaft, and a complementary feed-roll; a reciprocatory support for said picker and feed-mechanism; a separator; and means for actuating the separator.

In testimony whereof I affix my signature 70
in presence of two witnesses.

HENRY B. COOLEY.
